UNITED STATES PATENT OFFICE.

PER HENNING SODERLUND, OF ALAMEDA, CALIFORNIA.

AUTOMOBILE-DOOR CLOSER.

1,324,363.

Specification of Letters Patent.

Patented Dec. 9, 1919.

Application filed July 14, 1919. Serial No. 310,860.

To all whom it may concern:

Be it known that I, PER HENNING SODERLUND, a citizen of the United States, and a resident of Alameda, county of Alameda, 5 and State of California, have invented a new and useful Automobile-Door Closer, of which the following is a specification.

This invention relates to improvements in automobile doors, and more particularly to 10 closing means therefor.

Automobile doors are often carelessly left open by persons getting into and out of 15 automobiles and as the doors when open extend a considerable distance outwardly from the sides of the automobiles, they are frequently broken off or damaged, incident to driving into and out of garages or through narrow driveways and sometimes in passing or being passed by other vehicles. Besides 20 the likelihood of being broken or damaged, the doors when open are a menace to pedestrains and it is therefore the primary object of my invention to overcome all liability of breaking or damaging doors and 25 of injuring pedestrians by providing a door closer which will automatically close the doors in a reliable manner and without slamming or banging.

An object of the invention is to provide 30 a door closer of the character described which will be inexpensive, compact, not liable to cause the door to stick and fail to close, and easy to install, the entire device being concealed within the body of the automobile.

The invention possesses other advantageous features, some of which, with the foregoing, will be set forth at length in the following description, where I shall outline 35 in full, that form of the invention which I have selected for illustration in the drawings accompanying and forming part of the present specification. In said drawings I have shown one form of the device of my invention, but it is to be understood that I 40 do not limit myself to such form, since the invention, as expressed in the claims may be embodied in a plurality of other forms.

Referring to the drawings:

Figure 1 is a top plan view of an automobile having the door closer of my invention embodied therein, a portion of the door and body being broken away to show the closer.

Fig. 2 is a side elevation of my invention 55 showing parts broken away.

Fig. 3 is a horizontal sectional view of the closer of my invention.

Fig. 4 is a fragmentary horizontal sectional view taken through the hinge lever showing the construction thereof and the manner of attachment to the plunger.

My invention embodies an angular hinge member secured to the door and pivoted within a specially constructed hinge plate that is secured to the door jamb. A plunger 65 and a retractile spring are concealed within the side wall of the automobile body and I may house these elements in a cylinder, the latter to be secured to the hinge plate on the jamb. By means of a plate and links 70 of novel construction I connect the plunger with the angular hinge member in such a way as to avoid a great deal of friction and secure substantially the same amount of leverage on the plunger in opening the door. 75 I thus insure an automatic closing action which is free from all liability of the jamming or sticking and failure of the door to close, and at the same time provide for an easy opening of the door.

Countersunk in the door 1 is a hinge plate 2 secured thereto by fastening elements 3 and which carries an angular and preferably substantially L shaped hinge member or lever 4.

In the outer face of the door jamb 5 which is secured in the sill of the side wall 6 of the auto body, a hinge plate 7 is secured. This plate is substantially U shaped and the body thereof extends through the 90 jamb into the space 8 between the inner and outer faces of the wall 6. The ends of the plate are bent right angularly to the body to provide ears or flanges 9, the latter being countersunk in the jamb and secured 95 thereto by fastenings 10.

The hinge lever 4 extends into the U shaped plate 7 and at its free end is pivoted on a vertical hinge pin 11, which pin is mounted in the plate 7. The plate 2, lever 100 4, plate 7, and pin 11, constitute the hinge elements of the invention.

Pivottally secured to the rear end of the plate 7 by fastenings 12, is a spring case or cylinder 13 which is disposed within the 105 space 8 and is open at its front end and closed at its rear end. A plurality of perforations 14 are formed in the front end of the cylinder and there is provided an air vent 15 in the closed end of the cylinder. 110

Reciprocally mounted in the cylinder 13 is a plunger 16, provided on its inner end with a piston 17, the latter snugly engaging in the cylinder. A retractile spring 18 is 5 mounted upon the plunger and at one end abuts the piston 17 whereas its other end abuts the rear end of the plate 7. The plunger is adapted to extend through an elongated opening 19 formed through the plate 10 7 and is connected with the lever 4 by a lever extension plate 20 and a pair of links 21. The plate 20 is mounted for pivotal movement in a slot 22 formed in the lever 4, a pivot pin 23 being inserted through the 15 lever and plate and at a point intermediate of the ends of the lever. A stop shoulder 24 is defined at one end of the slot 22 and the plate 20 is provided with an enlargement or shoulder 25 which latter is normally 20 spaced from the shoulder 24. The links 21 are pivoted as at 26 to the plate 20 and as 27 to the end of the plunger 16.

When the door is opened a pull is communicated to the plunger 16 through the 25 lever 4, plate 20 and links 21 and the plunger yields against the action of the spring 18. The piston 17 is permitted to move freely in the cylinder 13, as the air in the cylinder will readily escape through the 30 perforations 14. The plate 20 moves on its pivot with the opening of the door a short distance, that is, follows the arcuate movement of the lever 4 and when the door has thus been opened a predetermined distance, 35 the shoulder 25 on the plate abuts the stop shoulder 24 on the lever and the plate becomes rigid with the lever and moves as an integral part thereof. The links 21 then move on their pivots and cause a pull in a 40 substantially straight line, which is in line with the plunger, to be communicated to the plunger. By thus obtaining a double link action through the initial relative movement of the plate 20 and the ordinary link 45 action of the links 21 the leverage on the plunger is constant, the plunger moves freely and with little friction, and a smooth non-jamming operation of the hinge is provided.

50 When the door is released after being opened the spring will retract and through the plunger, links, plate and lever, will close the door. The air trapped in the closed end of the cylinder 13, and against which the 55 piston 17 cushions, will escape slowly through the vent 15, check the closing action of the spring and thus prevent slamming or banging of the door. By having the cylinder pivoted to the plate 7, allowance is made for the slight lateral movement given the cylinder during the contracting 60 of the spring, and the cylinder is cut away and rounded as at 28 at the end thereof which is secured to the plate 7 to facilitate 65 such lateral movement. When the door is

in the closed position, the plate 20 is out of contact with the shoulder 25, and acts as a link, causing the pull of the spring to be exerted directly upon the pin 23, and causing the line of pull of the spring to pass 70 through the pin 23, thus holding the door tightly closed. As the door is opened, the plate contacts with the shoulder causing the plate to become rigid with respect to the lever and to move therewith, transferring 75 the line of pull of the spring to the pin 26, which moves in an arc, which does not depart to any great extent from the normal line of pull of the spring. By virtue of this construction, a concealed hinge having its 80 pivot pin 11 spaced from the edge of the door and substantially in line with the outer face of the door may be employed.

I claim:

1. The combination with an automobile body and a door therefor, of a hinge lever of less width than the door fixed to the edge of the door and hinged within the body, between the sides thereof, a plunger, a plate pivoted on the lever and pivotally connected with the plunger, means to prevent movement of the plate relative to the lever after the door has been opened a predetermined distance, and a spring against the action of which the plunger operates when the door is opened.

2. The combination with an automobile body wall and a door therefor, of a substantially L-shaped hinge lever fixed at one extremity to the door and hingedly connected at the other extremity to the wall, a plunger mounted in the wall, a plate pivoted to the lever at a point intermediate of the ends of the lever, a link pivotally connected with the plate and plunger, a stop shoulder on the lever to limit the movement of the plate relative to the lever after the door has opened a predetermined distance, and a spring against the action of which the plunger moves when the door is opened.

3. The combination with the wall of an automobile body and a door therefor, of an angular hinge lever of less width than the door fixed within the edge of the door at one end extending into and being hingedly connected with the wall between the sides thereof at its other end, a spring actuated member for closing the door carried in the wall, a plate pivoted to the lever intermediate the ends of the lever and pivotally connected with the spring actuated member, and a stop shoulder on the lever with which the plate engages when the door is opened a predetermined distance.

4. The combination with a wall of an 125 automobile body and a door therefor, of an angular hinge lever secured to the edge of the door, a hinge plate secured to and concealed within the wall, a hinge pin connecting the lever and plate, a plate pivoted to 130

the lever and extending outwardly therefrom in line with that portion of the lever which extends outwardly from the door edge, a plunger pivotally connected with the last-named plate, and a spring against the action of which the plunger moves when the door is opened.

5. The combination with a wall of an automobile body and a door therefor, of an angular hinge lever secured to the edge of the door, a hinge plate secured to and concealed within the wall, a hinge pin spaced from the edge of the door and connecting the lever and plate, a plate pivoted to the lever at a point remote from said pin and extending outwardly therefrom in line with that portion of the lever which extends outwardly from the door, a plunger pivotally connected with the last-named plate, a spring against the action of which the plunger moves when the door is opened, a cylinder connected to the hinge plate and housing the plunger and spring, and a pis-

ton carried by the plunger and working in the cylinder.

6. The combination with an automobile body wall and a door therefor, of an angular hinge lever fixed to one edge of the door and extending into the body wall between the sides thereof, a pivot for the inner end 30 of the lever within the wall, a plunger within the wall, a connection between the plunger and lever arranged to permit movement of the door relative thereto for a predetermined distance in opening the door and to move 35 with the door after such predetermined movement and a spring against the action of which the door is opened, connected with the plunger.

In testimony whereof I have hereunto set 40 my hand at San Francisco, California, this 3rd day of July, 1919.

PER HENNING SODERLUND.

In presence of—
H. G. PROST.
